UNITED STATES PATENT OFFICE

OLNEY B. MONOSMITH, OF LORAIN, OHIO

CARBURETER.

1,125,363.

Specification of Letters Patent.

Patented Jan. 19, 1915.

Application filed February 9, 1914. Serial No. 317,402.

To all whom it may concern:

Be it known that I, OLNEY B. MONOSMITH, a citizen of the United States, residing at Lorain, in the county of Lorain and State of Ohio, have invented certain new and useful Improvements in Carbureters, of which the following is a specification.

This invention relates to carbureters for internal-combustion engines, and more particularly to improvements in the construction of the carbureter set forth and described in my co-pending application filed July 7, 1913, and having Serial No. 777,637.

The main object of the present invention is to provide a carbureter, which operates substantially on the same principle as my said other design, but is still more simple in construction and will operate efficiently at varying speeds of the engine without requiring adjustment.

A further object of this invention is to provide means, whereby the waste heat from the exhaust of the engine may be utilized to warm some of the air entering the carbureter, or the exhaust gases may be supplied directly thereto.

Other objects will be readily understood as the invention is hereinafter fully described in connection with the accompanying drawings, which illustrate a preferred form of the same, and the novel features of the invention will be particularly pointed out in the appended claims.

In the drawings similar characters of reference designate like parts.

Figure 1 is a sectional elevation of my improved carbureter, Fig. 2 is an end elevation looking toward the float chamber after removing the air tube, Fig. 3 is a plan section view taken on the line 3—3 of Fig. 1, Fig. 4 is an elevation of the air tube looking in the direction of the arrow A Fig. 1, and Fig. 5 illustrates, on an enlarged scale, the shape of the air inlet perforations.

Referring to the drawings, the air tube is designated by 1, and its upper end is provided with a flange 2 for securing the same to the engine. One wall of the air tube, as indicated by 3, is provided with an opening 4, which is circular in form, its lowest edge being represented by 5. Arranged in the air tube 1 is an angular shaped separating plate consisting of a horizontal portion 6 and an inclined upwardly extending portion 7. The upper surface of the horizontal portion of said separating plate is in

alignment with the edge 5 of the opening 4. This separating plate extends the full width of the air tube 1, and may be secured in place by brazing, or other suitable means as indicated at 8. The horizontal portion 6 of said separating plate is provided with air admitting perforations 9, and the inclined portion 7 with similar perforations 10. It will be noticed that the perforations 9 and 10 are larger at the inner surface of the separating plate, or in other words, at the opposite side from the direction of the air currents entering therethrough.

Removably fixed to the wall 3, by screws 11 or in any other suitable manner, is a flange plate 12, which supports a float chamber 13, with an intervening compartment 14, arranged between the same and said flange plate. Interposed between the wall 3 of the air tube and the flange plate 12, is a thin plate of copper 15 or other suitable sheet packing, which is cut out as shown at 16 to form a space or well, for permitting the gasolene or other volatile fluid to flow from the float chamber, by way of a conduit 17, to the opening 4 of the air tube. In order to provide means for changing the size of the outlet end of the conduit 17, so that a flow economically proportionate to the consumption of gasolene for different kinds or horse-power of engine may be obtained from a standard or one size of carbureter, a plug 18, having such a size of opening 19 therethrough as will be found in practice to give the best results, is removably threaded into the flange plate 12. The opening 19 in the plug is larger at the outlet end than at its inner end. Said plug is slotted at 20 for a screw driver.

For admitting air to mix with the gasolene from the well 16, the flange plate 12 is provided with a plurality of apertures 21, which are located within the compartment 14 directly opposite the opening 4 in the air tube. These apertures are also made larger at the inner surface of the plate than at their other ends. Air may enter the compartment 14 through an inlet opening 22, but preferably exhaust gas is supplied thereto by means of a pipe 23 which leads from the exhaust of the engine, or the pipe 23 may be wound around the exhaust pipe of the engine and heated air thus supplied. For the purpose of feeding gasolene to the air tube 1 when first starting the engine, a groove or channel 24 is cut in the surface of

its wall 3, and extends from the edge of the well 16 to a terminus opening 25, which enters the air tube just above the edge of the throttle valve 26 when closed. The outline of the well 16 is represented by a dotted line in Fig. 4.

5 The perforations 9 and 10 in the separating plate of the air tube, the opening 19 in the plug 18, and the apertures 21 of the flange plate 12, are all preferably made in an angular shape as illustrated in Fig. 5. In all cases, the inlet ends are smaller than their other ends. It has been found by experiments, that when said openings are formed by a combination of tapering walls 27 and 28, a Venturi action is obtained by 10 gas or liquid entering the smaller ends of such openings, which produces even more satisfactory results than when the walls are made with a straight taper.

15 The float chamber 13 is provided with a removable cover 29, and in order to hold the same in place, a locking finger 30 is employed. This locking finger has a shank 31, which is slidably mounted in a recess of a lug 32 projecting from the float chamber. A washer 33 is fixed to the end of said shank, and interposed between the same and the lug 32 is a coiled spring 34, which is adapted 20 to retain the locking finger in its down position. When it is desired to remove the cover, the locking finger may be raised and swung out of engagement therewith, but when the finger is down, its shank binds 25 against the upper outer edge and lower inner edge of its recess, thereby preventing displacement of the cover.

30 In operation, the engine is started by first slightly opening the throttle valve 26, which causes the air to rush past the terminus opening 25, thereby creating a vacuum and drawing gasolene from the well 16 through the channel 24. As the throttle valve is opened more, the gasolene from the well 16 begins to flow in a thin film over the surface of the horizontal portion 6 of the separating plate, and the air rushing through the perforations 9 mixes with the same. Furthermore air enters the perforations 10; and air, 35 exhaust gases or heated air entering through the apertures 21, also mix with the gasolene, whereby a very uniform and efficient mixture is supplied to the engine with the most economical consumption of gasolene.

40 45 50 55 It will be understood that the construction or arrangement of the parts may be changed, so long as the same does not depart from the invention claimed.

Having fully described my invention, 60 what I claim is:

1. In a carbureter, the combination with an air tube having an opening in its wall, of a flange plate covering the opening, a float chamber carried by the flange plate, means 5 of communication from the float chamber to

an edge of said opening, and a perforated plate arranged transversely of the air tube at that side of the edge of said opening communicating with the float chamber, substantially as described. 70

2. In a carbureter, the combination with an air tube having an opening in its wall, of a flange plate covering the opening, a float chamber carried by the flange plate, means of communication from the float chamber to 75 an edge of said opening, a perforated plate arranged transversely of the air tube at that side of the edge of said opening communicating with the float chamber, and said flange plate being provided with apertures 80 opposite said opening, substantially as described.

3. In a carbureter, the combination with an air tube having an opening in its wall, of means for supplying a volatile fluid to an 85 edge of the opening, a plate arranged in the air tube at that side of the edge of said opening supplied with volatile fluid, the plate being provided with perforations, and the perforations being larger at the side of the 90 plate adjacent the edge of said opening supplied with volatile fluid, substantially as described.

4. In a carbureter, the combination with an air tube having an opening in its wall, of 95 a flange plate covering the opening, a float chamber carried by the flange plate, means of communication from the float chamber to an edge of said opening, a perforated plate arranged transversely of the air tube at that 100 side of the edge of said opening communicating with the float chamber, said flange plate being provided with apertures opposite said opening, and the apertures being larger at their inner ends, substantially as 105 described.

5. In a carbureter, the combination of a vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, and a perforated plate arranged transversely of said air tube below said opening, substantially as described. 110 115

6. In a carbureter, the combination of a 120 vertical air tube, the air tube having an opening through its wall, a flange plate fixed to the air tube and covering the opening, a float chamber carried by the flange plate, a sheet of material interposed between said 125 flange plate and said air tube, a conduit from the float chamber, said sheet being cut out to establish communication from the conduit to the lower edge of said opening, a plug, the plug having a tapering hollow 130

center in alinement with the conduit, the outlet of the plug being the larger, and a perforated plate arranged transversely of said air tube below said opening, substantially as described.

7. In a carbureter, the combination of a vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, said flange plate being provided with apertures opposite said opening, the apertures being larger at their inner ends, a plate arranged transversely of the air tube below said opening, the plate being provided with perforations, and the perforations being larger at the upper side of the plate, substantially as described.

8. In a carbureter, the combination of a vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, a perforated plate arranged transversely of said air tube below said opening, said flange plate being provided with apertures opposite said opening, and means whereby heated air is conveyed to said apertures, substantially as described.

9. In a carbureter, the combination of a vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, a perforated plate arranged transversely of said air tube below said opening, said flange plate being provided with apertures opposite said opening, a compartment covering said apertures, and means for conveying exhaust gases from the engine to the compartment, substantially as described.

10. In a carbureter, the combination of a

vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, a perforated plate arranged transversely of said air tube below said opening, and the perforations being larger at the upper side of the plate and consisting of a combination of tapering and more tapering walls, substantially as described.

11. In a carbureter, the combination of a vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, a separating plate consisting of a horizontal and inclined portion arranged in the air tube, the horizontal portion of the separating plate being below said opening, the separating plate being perforated, and the perforations being larger at the inner surfaces of the horizontal and inclined portions, substantially as described.

12. In a carbureter, the combination of a vertical air tube, the air tube having an opening through its wall, a flange plate fixed to the air tube and covering the opening, a float chamber carried by the flange plate, a sheet of material interposed between said flange plate and said air tube, a conduit from the float chamber, said sheet being cut out to establish communication from the conduit to the lower edge of said opening, a perforated plate arranged transversely by said air tube below said opening, a throttle valve in the air tube above the perforated plate, and the air tube being provided with a groove leading from the cut out portion of said sheet to a point above the throttle valve when in closed position, substantially as described.

In testimony whereof I affix my signature in presence of two witnesses.
